COLLAPSIBLE STOCK FOR HANDGUNS

Russell M. Catron, Monterey, Calif.

Application May 29, 1950, Serial No. 165,023

7 Claims. (Cl. 42—72)

1

The invention forming the subject matter of this application relates to a semi-automatic or automatic hand gun and holster combination which may be converted into an effective machine pistol.

It is an object of the invention to provide a holster member for a hand gun which will be effective as a container and readily convertible as a stock for the same when a shoulder rested weapon is desired. A further object is the minimum modification of the hand gun to render it susceptible for conversion with the holster member to a shoulder rested weapon.

Summarizing the invention, the holster element is provided with the requisite sheathing characteristics to accommodate and carry a hand gun, with due regard for ready access, and incorporates features essential to render the hand gun an effective shoulder rest weapon from the standpoint of rigidity and comfortable aim and ease of firing. The holster carries a collapsible bracing member which, when extended, serves to effectively interlock gun and holster into a rigid shoulder rested weapon. The hand gun is modified only to the extent of providing a two-point connection with the holster and to permit the employment of the magazine as a detachable foregrip.

In the drawings forming a part hereof, wherein a preferred form of the invention is shown,

Figure 1 is a side elevation of the holster and gun with the latter sheathed in the former;

Figure 2 is a bottom plan view of the combination of Figure 1;

Figure 3 is a side elevation of the holster and hand gun interconnected in the assembly providing a machine pistol;

Figure 4 is a longitudinal sectional view of the holster member with the brace carried thereby in extended position and including fragmentary portions of the gun to show the connector means;

Figure 5 is a sectional view taken along the line 5—5 of Figure 3;

Figure 6 is a sectional view taken along the line 6—6 of Figure 4;

Figure 7 is a sectional view taken along the line 7—7 of Figure 3, and

Figure 8 is a fragmentary elevational view of the back of the hand gun to illustrate the lower holster connection.

The numeral 10 denotes the holster member which when attached to a hand gun 11, in the manner illustrated in Figure 3, has the overall appearance and function of a shoulder rested weapon stock. The holster is formed of an inner

2

shell 12 of relatively light but strong sheet metal, having an inner and outer covering 13 and 14, respectively, of material such as leather or webbing, to provide a pliable, wear-resistant surface which will not mar the finish of the gun. The leather or webbing is molded into close adherence with the shell 12 and has its edges lapped thereover and secured, as by the stitching 15, or cementing.

10 The main body of the holster 10 is cylindrical in cross section to accommodate the barrel and slide portion of the gun, and has a pair of spaced, rearwardly tapering wings 18 and 19 extending longitudinally thereof and projecting outwardly therefrom. As will be seen in Figure 7, the wings 18 and 19 are integral with the shell 12, being extensions thereof bent outwardly in normally converging relationship but susceptible of being spread for lateral removal of the gun from the holster through slot 20, as will presently appear.

A semi-flexible flap 25 is formed at the butt end of wing 18 of the holster by continuing the leather covering members 13 and 14 thereof and stitching or otherwise joining their edges. This flap serves the dual purpose of carrying connector means, such as the spring eye fasteners 26, by which the holster may be swung from a shoulder harness or waist belt, and of providing a recoil pad when it is folded over the end of the holster as the unit is set up as a shoulder rested weapon. The spring eye fasteners are set with the heads angled inwardly at such an angle that they securely fasten the holster to a carrier member, but will yield to a single pull exerted above and between them to free the holster for use as a stock.

Forwardly in the holster 10, in alignment with and serving as an end for the cylindrical portion 12 thereof, there is provided a barrel muzzle cup 28, which may be of flexible material, such as leather, secured therein in any conventional way, such as by the rivets 29. This cup also serves as a positioner and guard for the firer's cheek and eye.

45 The forepart of the holster 10 is fashioned into a downwardly turned lip 32, a portion of which is adapted to receive the upper rearwardly projecting end of the receiver frame 33 of the gun 11. A post 34, seated within the lip 32, and formed as 50 an integral part of a rearwardly extending bracing piece 35 secured between the shell 12 and its inner covering 13, as by the rivets 36, enters an aperture 37 in the gun receiver frame 33 to make one of the two connections between gun 11 and holster 10 (see Figure 4).

A channel-shaped arm 40, pivotally connected at 41 to a member, hereinafter described, secured to the shell 12 of holster 10, has a downwardly turned hook 42 on its opposite or free end. This hook is engageable with a slit 43 cut in the breakdown plug 44 of gun 11, to provide the second connection between gun and holster in the assembly of the members into a shoulder rested weapon. Additionally, the forward end of the arm 40 is flared into wings 45 which bear against the sides of receiver frame 33 of gun 11, for added bracing.

A means of locking the two connections of gun and holster just described is supplied by the channel-shaped spreader or bracing link 48. The lower end of the link is pivotally connected, as at 50, to arm 49 in spaced relation to its hooked end 42, and the opposite or upper end of the link carries a pin 51 riding in the slot 52 of the housing 53 secured on the under side of holster 10. Within the housing 53 a coiled spring 57, abutting a chock 58 which is in juxtaposition to pivot 41, and is secured to shell 12 of the holster 10, carries at its opposite end a follower piece 59 normally bearing against the pin 51 on arm 48. A spring clip 60 secured to the shell 12 of holster 10, has a lip disposed to engage the pin 51 as it is moved to the forward end of the slot 52 of housing 53.

In order to permit the use of the magazine or clip 65 as a foregrip, the underside of the barrel 66 of gun 11 is cut away, as at 67, in the manner illustrated to best advantage in Figures 1, 2, 3 and 5, to provide a seat for the magazine bottom plate 68. At its forward end the cut away of the barrel is rounded, as at 69 (see Figure 5) with a slight undercut, as at 70 (see Figure 3) to receive a rounded end of the magazine bottom plate 68. At its rear end the cut away portion 67 terminates in a slot 71 (see Figures 2 and 3) to receive the opposite end of plate 68 which, in this instance, is tapered at its leading edge, as at 72, to facilitate entry thereof. Additionally, the end of the plate is notched at 73 to engage a spring urged ball detent 74 positioned in a bore 75 terminating in slot 71.

From the foregoing, the operation of the device will be readily understood as follows: assuming the holster 10 is being used to sheath the gun 11, as in Figures 1 and 2, the bracing linkages 40 and 48 will be collapsed and nested, and the clip or magazine 65 will be housed in the receiver frame. This unit will be supported by the spring eyes 26 from shoulder harness or a waist belt. The nesting of the bracing linkages was accomplished by the release of spring clip 60 from its engagement with the pin 51 of link 48 which is then freed to move about its pivot 50 and compress spring 52, at the same time drawing arm 40 upwardly on its pivotal connection with ear 41. As link 48 is channel-shaped in cross section, it will envelop a portion of housing 53 and the two will be, in turn, covered by the channel-shaped arm 49, in the manner shown in Figure 1, and held in this position by over-center pressure of spring 57 and engagement of pin 50 with the back of spring clip 60.

While the gun 11 is most conveniently inserted into the holster lengthwise, that is to say, muzzle end first, the draw is effected by grasping the grip and pulling the same downwardly and outwardly, which serves to enlarge the slot 20 and spread the wings 13 and 19 for passage of the same.

When the gun 11 has been withdrawn from

the holster, arm 40 is grasped by its hooked end 42 and swung away from the holster. Post 34 is inserted in the aperture 37 of the receiver frame 33, and the hook 42 is inserted in slot 43 in pin 44. Link 48 is then swung about its pivot until pin 51 is snapped into engagement with spring clip 60 locking the holster, now serving as a stock, into rigid connection with the hand gun 11. When pin 51 is in engagement with clip 60, the link 48 is in over-center position with respect to the thrust exerted on said link by link 40. Next clip or magazine 65 is removed from the gun receiver 33, by simple release of the catch 76, and inverted for engagement of its bottom plate 68 with the cut away 67 in the bottom of the barrel 66, by inserting an end in the undercut 69 and twisting the leading edge 72 of its opposite end into slot 71 to permit detent 74 to engage the notch 73 to lock it in place. The clip 65, now employed as a foregrip may now be replaced with a clip 78 of greater cartridge capacity.

The weapon is now ready for firing, being put into position by grasping the primary grip of the gun in the right hand and the foregrip with the left, and raising the butt end of the holster 10 against the shoulder. As hereinabove stated, flap 25 as pressed against the shoulder serves as a modified recoil pad.

While a preferred embodiment of the invention has been shown and described, it is to be understood that all substantial equivalents of said embodiment are within the scope of the invention.

What I claim as new and desire to secure by Letters Patent is:

1. The combination of a hand gun and a shoulder stock therefor, with said hand gun and stock being provided with means for securing the latter to the former, said means comprising catch means carried at the tip of the stock and engageable with a rearwardly projecting upper portion of the gun receiver frame to constitute a first point of attachment between said gun and stock, a link pivotally connected at one end to the underside of said stock, and having catch means at its other end engageable with the hand gun butt at the lower portion of the rearward side of the same to constitute a second point of attachment between said gun and said stock, and means for maintaining said stock tip and said other end of said link in spaced relation to thereby preserve the attachment of their respective catch means with said gun comprising a second link having one end pivotally connected to said first link intermediate the ends of the latter and having its other end slidably connected to said stock, so that upon a predetermined degree of sliding of said other end of said second link toward said stock tip the catch means of said stock tip and said first link will be pressingly maintained in attached relation to said gun.

2. The combination set forth in claim 1 wherein the catch means for the stock tip comprises a dowel pin upwardly insertable within an aperture of said gun receiver frame and the catch means for said first link comprises a hook member downwardly insertable within a slot provided in the gun butt.

3. The combination set forth in claim 2 wherein a spring clip means is provided in fixed relation to the stock and operable to yieldingly maintain the slidably end of the second link in position after said predetermined degree of sliding.

4. The combination set forth in claim 2 wherein a spring means carried by said stock in asso-

ciation with the slidable end of said second link urges said end toward said stock tip.

5. The combination of a hand gun and a shoulder stock therefor, with said hand gun and stock being provided with means for bracingly attaching the tip of said stock to the gun, said means comprising, for the stock, a link having one end thereof pivotally secured to the stock at the underside thereof at a point located rearwardly of the tip of the stock, first catch means carried at the tip of said stock and second catch means carried at the other end of said link, and, for the gun, first catch means located at a rearwardly projecting portion of the gun receiver frame and second catch means located at the rearward side of the gun butt, with said first and second catch means for the gun being complementary, respectively, to the first and second catch means of the stock and enabling their mutual engagement upon a relative pivoting movement between said stock and link, and means for securing the pairs of catch means together comprising a member having a pivotal connection with one of said stock and link members and a slidable connection with the other, whereby said stock and link members may be positionally braced in attached relation with the gun.

6. For a hand gun, an attachment member in the general form of a shoulder type stock adapted to be secured to the gun to convert the same to a shoulder-restable weapon, said member being provided with means at its forward end engageable with an upper and rearward portion of the gun receiver frame, and means carried by said member and adapted to form a bracing connection between said member and a portion of the hand gun located below and in spaced relation to said portion of said receiver frame, said means adapted to form said bracing connection comprising a link pivotally secured at one end to said member at the underside thereof at a point located rearwardly of the forward end of said

member, said link being provided at its other end with means enabling its attachment to the hand gun, and a spreader member having a slidable connection with said attachment member and a pivotal connection with said link operable upon a predetermined degree of movement of the slidable end thereof in the direction of the forward end of said attachment member to lock said link in angularly disposed relation to said attachment member.

7. For a hand gun, an attachment member therefor comprising a substantially triangularly shaped sheath open at the top and along one side thereof and having a closed side, said sheath having normally converging flexible wing portions adapted to embrace and retain a gun within said sheath against accidental removal through the open side thereof, said wing portions being yieldingly divergable to allow a forced removal 15 of the gun through the open side of the sheath, a socket member adjacent the lower end of the sheath adapted to receive the end of the barrel of the gun for the support of the gun within the sheath, and means at the tip of the lower end 20 of the sheath and at the closed side of the sheath comprising a two point connection for securing the sheath to the rearward end of the gun in 25 shoulder stock position.
